[57] CLAIM

The ornamental design for an anatomically correct head support, as shown and described.

DESCRIPTION

FIG. 1 is a top plan view of a first embodiment of an anatomically correct head support showing my design;

FIG. 2 is a front elevational view thereof;

FIG. 3 is a side elevational view thereof, both sides being essentially the same;

FIG. 4 is a rear elevational view thereof;

FIG. 5 is a bottom plan view thereof;

FIG. 6 is a reduced rear side perspective view of the head support depicted in FIGS. 1-5;

FIG. 7 is a top plan view of a further embodiment of an anatomically correct head support embodying my new design;

FIG. 8 is a front elevational view thereof;

FIG. 9 is a rear elevational view thereof; and

FIG. 10 is a side elevational view thereof.
